HYDRAULIC JACK

James Stewart Rothery, Ilford, England

Application October 28, 1941, Serial No. 416,881
In Great Britain June 24, 1941

10 Claims. (Cl. 121—46)

This invention relates to means for locking the extended ram of an hydraulic jack against unintentional collapse which might occur owing to small leakage or other reason and to a packing for use with hydraulic rams.

According to one feature of the invention the ram of an hydraulic jack is provided with a number of superposed holes through it, preferably in vertical alignment, and around the ram resting on the head of the jack frame or structure or of the cylinder is a rotatable sleeve having in it a plurality of holes preferably in pairs, the two holes of each pair being diametrically opposite each other and the pairs of holes arranged at differing heights in the sleeve so that to whatever height the ram may be lifted the sleeve can be rotated so as to bring one of the pairs of holes in it opposite or nearly opposite to, i. e., substantially into coincidence with, a hole in the ram after which a pin, say on a chain, is inserted from one side of the sleeve through the hole therein and through the hole in the ram and the corresponding hole on the other side of the sleeve.

It will be seen from the above that when the ram has been extended to the desired height the sleeve is rotated until the pin can be pushed through the pair of holes coinciding with a hole in the ram which is then locked and any drop will not exceed, at the most, the vertical distance between the centres of one pair of holes in the sleeve. A secondary sleeve (or other device) screwed inside or outside the main sleeve could be arranged to take up this "play" if desired but such fine adjustment is not usually required.

Sufficient adjustment may also be obtained by having the holes elongated, the line of elongation rising slightly so that a fractional turn of the sleeve gives the required adjustment.

The diametral holes in the ram preclude the satisfactory provision of a packing gland at the top of the cylinder and in order to prevent the escape of working liquid that leaks past the cup leather or like normal ram packing a safety seal has been devised and applied to the ram above the said cup leather or the like, in accordance with a further feature of the invention.

In order to prevent the jack being raised beyond a predetermined height the cylinder has a vent or an exhaust valve which, when communicating with the pressure chamber of the jack owing to the jack being raised to the said height, allows the working liquid to return to the reservoir. Such an arrangement is disclosed in the specification of my U. S. Patent No. 2,214,440.

According to a still further feature of the invention, however, the said valve is of non-return type whereby liquid is prevented from returning to the cylinder when the jack is lowered and escaping by way of the unpacked top of the cylinder.

The safety seal and the vent with the non-return valve may be used with other types of hydraulic jacks, for example, jacks having externally screw-threaded rams on which is a nut which can be set longitudinally of the ram to sustain it by thrusting against the top of the jack.

The invention will now be described with reference to the accompanying drawings wherein:

Fig. 1 is a perspective view of the jack, the ram being lowered;

Fig. 2 is a side elevation, partly in section, showing the top of the jack cylinder, the rotatable sleeve and the lower part of the ram with a safety seal.

Fig. 2^a is a detail of a modified form of safety seal.

Fig. 3 is a fragmentary view of a jack incorporating a secondary sleeve for fine adjustment purposes; and

Fig. 4 is a fragmentary view of a jack incorporating a sleeve with elongated holes.

The jack shown in Fig. 1 comprises the tubular tripod 1 from the peak of which the ram cylinder 2 depends, the legs being braced together by hollow members 3 and being braced to the cylinder 2 by hollow members 4. A pump 5 is fixed to the base of the ram. The pump draws liquid from the reservoir formed by the hollows of the legs of the tripod and of the members 3 and 4 and delivers it to the bottom of the cylinder to raise the jack; and a release valve 6 allows liquid to flow from the cylinder and into the reservoir to allow the ram to sink. The jack as described so far is substantially as described in my said U. S. patent specification No. 2,214,440.

According to one feature of the present invention the ram 7, Fig. 2, is provided with a number of pairs of vertically superposed holes 8, the holes of each pair being diametrically opposite to each other, and around the ram and resting on a guide collar 9 for the ram is a sustaining element comprising a rotatable sleeve 10 in which are a number of pairs of holes 11. The centres of the holes 11 lie on a double helix so that each hole has another diametrically opposite to it and each pair of holes is at a different height from the others. The guide collar 9 is

flanged at 12 and the flange rests on the top of the cylinder 2.

In use, the jack is raised, i. e., the ram is lifted, to bring the crutch 13 (Fig. 1) into engagement with the article to be sustained, the sleeve 10 is turned to bring two of its holes into register with a pair of holes 8 and a pin 14 is thrust into the four aligned holes and locks the ram in the raised position, the ram thrusting downwardly on the pin if able to overcome the pressure of the working fluid, the pin thrusting on the collar and the collar thrusting on the cylinder through the flange 12 of the guide collar.

The collar 9 is provided in lieu of a packing gland. To overcome the disadvantage arising from the absence of a gland at the top of the cylinder the ram is provided with a safety seal 15. This seal is located at the reduced bottom of the ram above the usual cup leather 16, said cup leather being secured to the ram by means of a washer 17 and a bolt 18 which enters a plug 19 forced into the bottom of the ram.

The seal comprises a packing ring 20 in the lower annular surface of which is a V-groove; and an expander ring 21 of triangular cross section but less in height as regards the V section than the groove is deep lies in the groove so as to expand the lips of the groove first. The expander rests on the upper portion of that part of the surface of a flange 22 on the plug 19 which projects beyond the sides of the ram whilst a movable collar 23 with an external flange 24 at its bottom end rests on the top of the ring 20. Above the collar 23 and bearing against the shoulder 25 on the ram formed by reducing the latter is a collar 26 like 23 but inverted, the flange 27 of said collar 26 thus being at the top; and between the flanges 27 and 24 is a spring 28 which thrusts the collar 23 into contact with the ring 20. The ring in turn thrusts against the expander and as the expander is held against downward movement relatively to the ring by the flange 22 the lips of the groove in the ring are splayed and make close contact with the cylinder and the outer surface of the ram, respectively. Liquid which leaks past the leather 16 is able to raise the seal 15 until the collar 23 butts against the collar 26. Thereafter the liquid is trapped until pressure on the leather is released whereupon the spring is able to expand to the position shown and the seal 15 drives the liquid back into the cylinder past the said leather. Either collar (23, 26) may be considerably shorter than shown and the other as shown or longer. Spring means may be employed to expand the cup leather in order to ensure that the seal 15 does not do all the work of the said leather.

A seal comprising a groove and expander having sections differing from a V may be used. Fig. 2^a shows one alternative form. In this case the underside of the ring 20 has a groove 20^a of half round section and the expander ring 21 is of corresponding shape, the radius of curvature, however, of the top of the expander being greater than that of the groove to ensure outward movement of the groove lips by the expander.

If the jack be laid on its side or inverted the seal 15 will prevent the flow of liquid to that end of the cylinder at which the collar 9 is located.

When the bottom of the ram nearly reaches the top of the cylinder the leather 16 passes a hole 28 in the cylinder and further upward movement of the ram is prevented as the hole allows the working liquid to escape from the cylinder. The liquid is conducted to the hollow of

one of the members 3 by means of a valve 29 and a pipe 30; and in accordance with the invention the valve 29 is of non-return type so that the liquid cannot flow back into the cylinder and escape past the collar 9 if the jack is laid on its side or is inverted.

In Fig. 3 an externally screw-threaded, hollow bush 31 is interposed between the flange 12 and the collar 10, the lower part of the bore of the said collar being screw-threaded for engagement with the bush. Thus the collar 10 can be raised or lowered to permit of adjustments which are fractional parts of the vertical distance between any two successive holes 11.

In Fig. 4 the collar 10 has holes 32 arranged similarly to the holes 11, Figs. 1, 2 and 3, but of elongated form, the major axes of the holes lying on the helices on which the centres of the holes lie. Thus, the collar permits of finer setting of the jack than is possible with the collar shown in Figs. 1 and 2 as parts of a pair of elongated holes can be exactly registered with two holes as 8 by turning the collar through an angle less than that lying between the centres of two successive holes.

What I claim is:

1. On an hydraulic jack comprising a cylinder, a ram operative in the cylinder, a ram sustaining element encircling the ram and supported solely by the cylinder and freely rotatable with respect to the ram and cylinder, said element having holes along its length at different distances from its ends and said ram having holes along its length, and a free pin to be passed through transversely registering holes in the sustaining element and in the ram whereby the ram is held against sinking with relation to the cylinder.

2. On an hydraulic jack comprising a ram in a cylinder, a freely-rotatable sleeve mounted on said jack in surrounding relation to said ram at the top of the cylinder, said sleeve having holes in diametrically-opposed pairs along its length, each pair of holes being at relatively different distances from its ends and said ram having holes along its length, and a free pin, said pin being adapted to enter a hole in the sleeve and a hole in the ram whereby the ram is held against sinking with relation to the jack cylinder.

3. On an hydraulic jack according to claim 2, said sleeve having holes the centres of which lie on a helix.

4. On an hydraulic jack according to claim 2, wherein the sleeve is vertically adjustable with respect to the ram and wherein the centers of the respective diametrically-opposed pairs of holes lie on helices and said ram having diametral holes.

5. On an hydraulic jack according to claim 2, said sleeve having elongated holes the centres of which lie on a helix and the major axes of which rise slightly.

6. On an hydraulic jack according to claim 2, said sleeve having a screw-thread, a screw-threaded bush engaging with said screw-thread on said sleeve, said bush being rotatably mounted on the jack.

7. In an hydraulic jack according to claim 2, a guide collar arranged between the ram and cylinder and providing a bearing contact for the ram, said collar being mounted in the upper end of the cylinder, a flange on said guide collar bearing against the top of the cylinder, and said

sleeve bearing directly on and being freely rotatable with respect to the guide collar.

8. In an hydraulic jack according to claim 2, said jack comprising tubular legs forming a fluid reservoir for serving the jack and said cylinder having a vent near its upper end and said ram being adapted to uncover the vent when the ram is raised to a predetermined extent, a non-return valve having its inflow side connected to the vent and its outflow side connected to the hollows of said tubular legs, and means for directing the fluid from such reservoir under pressure for operating the ram.

9. A construction as defined in claim 2, wherein means are provided for preventing any leakage of operating fluid from reaching the sleeve.

10. A construction as defined in claim 2, wherein spring operated means are provided to prevent leakage of operating fluid from reaching the sleeve, and wherein such spring-operated means automatically returns such leakage for power service on the ram.

10
